J. S. Brown.

UNITED STATES PATENT OFFICE.

ALBERT T. L. DAVIS, OF LAKE VILLAGE, ASSIGNOR TO THE PITMAN MANUFACTURING COMPANY, OF LACONIA, NEW HAMPSHIRE.

STOP-MOTION MECHANISM FOR KNITTING-MACHINES.

SPECIFICATION forming part of Letters Patent No. 400,063, dated March 26, 1889.

Application filed February 23, 1888. Serial No. 264,940. (No model.)

To all whom it may concern:

Be it known that I, ALBERT T. L. DAVIS, a citizen of the United States, residing in Lake Village, in the county of Belknap and State of New Hampshire, have invented an Improved Stop-Motion Mechanism for Knitting-Machines; and I do hereby declare that the following is a full and exact description of the same, reference being had to the accompanying drawings, making part of this specification.

Figure 1 of the drawings is a side view of my improved mechanism; Fig. 2, a side view of the same, taken at right angles to the view in Fig. 1.

Like letters designate corresponding parts in both figures.

In the drawings, A represents the power-shaft, and B the driving-shaft, of a knitting-machine, connected with or geared to the machine in any usual or known manner. Upon the shaft A are two (preferably grooved) pulleys, *a a*, at a little distance apart, as indicated in the drawings, and on the shaft B are two other corresponding pulleys, *b b*. From each pulley *a* to the opposite or corresponding pulley, *b*, a belt, C, passes. The two belts C are loose or slack on their pulleys, and require binders to make them tight for transmitting power and motion to the driving-shaft. For tightening the belts two movable binding-pulleys, D D, are employed to be pressed against the belts. As shown in the drawings, these binding-pulleys are mounted on sliding bars E E, which terminate in suitable handles, *d d*. I have shown also the pulley-pivot *f* of each binder-bar as supported and adjusted in a slot, *e*, of the bar, which slides in a part of the frame on which the device is mounted. The bars near the outer or handle end rest and slide on a transverse catch-bar, G, or its equivalent, and there is a notch, *g*, in the under edge of each binder-bar adapted to catch upon the catch-bar when the binder is pushed against the belt, and thereby to hold the belt taut. There is also a transverse sliding bar, H, for the purpose of lifting the binder-bars sufficiently to free their notches from the bar G and allow the belt to push back the binder to stop the motion of the belt and of the whole machine. In

the upper edge of this lifting-bar are inclined surfaces or cam-faces *h h*, one being shown at one end of a notch and the other at the end of the bar. The arrangement of this lifting-bar in connection with the two binder-bars is such that when the lifting-bar is in the position shown in Fig. 2 either one of the bars is or may be depressed and catch over the catch-bar; but when the lifter-bar is moved endwise to the proper extent the binder-bars will be lifted by the adjacent cam-faces sufficiently to lift them from the catch-bar and allow the binder to be set free and the belts to be slackened to stop the machine. Since only one binder-bar is ever fastened upon the catch-bar, the lifting-bar never acts on but one binder-bar at one time, and when it has lifted a binder-bar from the catch-bar both binder-bars are free and the machine stops. Either binder may thus be brought into action and released. The two driving-belts are used alternately, one passing around a larger driving-pulley *a* and the other around a smaller pulley *a*, so as to drive the machine at a greater or less speed, as required, or by different-sized receiving-pulleys *b b*, if preferred. It is to be understood, however, that the stop mechanism is applicable to single belts and pulleys as well as to double, as shown.

The binders are set free automatically and their times automatically regulated by a pattern-chain or its equivalent by means substantially as follows: On the driving-shaft B is a cam, I, which as the shaft revolves acts upon the arm *i* of a vibratory cam-lever, J, pivoted to the frame at *k*, so that the lever is vibrated at each revolution of the driving-shaft, the lever being retracted by a spring, *l*. On a projecting arm, *m*, of the lever is a cam, K, which as the arm is vibrated up and down acts upon the rear end of a pawl, L, represented as sliding in ways *n n* of the frame and retracted by a spring, *o*. The pawl acts upon a ratchet-wheel, M, on a shaft, *p*, which carries the sprocket-wheel N of a pattern-chain, O. The pattern-chain has its cam projections *r r* at the required distance apart to release the binder after the notched wheel has been turned as many notches as are equal to the number of revolutions of the driving-

shaft B required to cause the requisite length of the knit web before stopping the machine. The cam projections *r r* may act, as shown, directly on the releasing-bar H to lift the 5 binder-bars from the catch-bars. The releasing-bar is retracted by a spring, *s*, or other suitable means. The arm *m* of the lever J terminates in a handle, by which the pawl L, and consequently the ratchet-wheel M and 10 sprocket-wheel N, may be moved by hand.

The whole device as constructed is very simple and compact.

This stop mechanism is applicable to any machine requiring automatic stopping.

15 I claim as my invention—

The combination, with the power-shaft pro-

vided with the pulleys *a a*, driving-shaft B, provided with the pulleys *b b* and cam I, belts C C, binding-pulleys D D, binder-bars E E, catch-bar G, and lifting-bar H, of the vibratory 20 lever J, actuated by the cam I and provided with the cam K, the pawl L, ratchet-wheel M, sprocket-wheel N, and pattern-chain O, provided with cam projections *r r*, substantially as and for the purpose herein set forth. 25

In witness whereof I have hereunto signed my name in the presence of two subscribing witnesses.

ALBERT T. L. DAVIS.
